LAMP

Henry J. Sauer, Fairfield, Conn., assignor to The Kilborn-Sauer Company, Fairfield, Conn., a corporation of Connecticut

Application April 17, 1944, Serial No. 531,342

6 Claims. (Cl. 240—41.5)

1

The present invention relates to an improvement in lamps, especially for automobile use. At present, a large majority of automobile lamps employ a so-called "Sealed Beam" type of lighting unit wherein the reflector and lens constitute a sealed container for the lamp filament. In mounting such unit in a casing provision must be made for supporting it within the casing and removably retaining it in place, and for this purpose the usual lamp casing consists of a body having means within it for engaging the rearward surface of the peripheral flange of the unit and a detachable flanged rim engaged upon the forward open side of the body to engage over the forward side of the flange of the unit to retain it in place.

It is an object of the present invention to provide a lamp casing, especially adapted for receiving a "Sealed Beam" type of lighting unit, wherein the supporting and retaining means for the unit constitute an integral or inseparable part of the body of the casing, thus providing a structure which is relatively economical to manufacture and which greatly facilitates the assembly of the lighting unit and its removal and replacement when necessary.

Another object is to provide a casing structure adapted to tightly retain the lighting unit through adjustable pressure applied thereon, so that relative looseness between the unit and the casing is effectually eliminated.

With the above and other objects in view, embodiments of the invention are shown in the accompanying drawing, and these embodiments will be hereinafter more fully described with reference thereto, and the invention will be finally pointed out in the claims.

In the drawing:

Fig. 1 is a front elevation of an automobile lamp, according to one exemplary embodiment of the invention.

Fig. 2 is a side elevation, partially in vertical section.

Fig. 3 is a front elevation of the lamp casing with the lamp unit removed.

Fig. 4 is a horizontal sectional view, taken along the line 4—4 of Fig. 3.

Fig. 5 is a side elevation, partially in vertical section, of a lamp casing according to a modified form of the invention, the lighting unit being removed.

Fig. 6 is a fragmentary sectional view showing the casing of the invention with a lens and reflector of separable type engaged therein.

Similar reference characters indicate corre-

sponding parts throughout the several figures of the drawing.

Referring to the drawing, and more particularly to Figs. 1 to 4 thereof, the lamp according to the illustrated exemplary embodiment of the invention shown therein, comprises a casing 10, preferably formed of sheet metal provided at its forward open side with a circumferential rim part 11, integrally connected to the body 10 of the casing by an inwardly projecting abutment flange 12, of U-shape in cross-section, and provided at its forward edge with an inturned retaining flange 13. At its bottom point the rim part 11 is provided with a relatively wide split 14, extending from its front surface to a point spaced slightly forwardly of the abutment flange 12 where it meets the medial point of a circumferential cut 15 extending upwardly at each side of the rim part to points spaced a short distance below the central diametric plane of the lamp, this cut being parallel to and spaced slightly in front of the abutment flange 12. Thus the portion of the rim part defined by the cut 15 constitutes a flexibly movable part which may be moved outwardly or inwardly with respect to its normal concentric relation to the rim part.

Rigidly secured to the outer peripheral surface of the opposed portions of the rim at each side of the split 14 is a pair of tubular brackets 16, secured by rivets 17 and engaged by a tightening screw 18 having its head bearing upon the end of one of the brackets and engaged with a nut 19 bearing upon the end of the other bracket. By tightening of this screw the flexibly movable part of the rim may be drawn inwardly, the width of the split being sufficient to permit this action to a substantial degree.

Upon the inner surface of the casing, rearwardly of the abutment flange 12, there is provided a pair of spaced retaining lugs 20, secured by rivets 21 and adapted to receive the positioning lug provided upon the lamp unit, as will presently more fully appear.

The "Sealed Beam" lamp unit consists of a reflector part 22 and a lens part 23, sealed together to constitute a sealed container for the lamp filament, a peripheral flange 24 being provided between the reflector and lens parts having at its rearward side an annular shouldered recess 25 for fitting engagement against the abutment means within the lamp casing, and at its forward side an annular shouldered recess 26 for retaining engagement therewith of the usual retaining rim. Inwardly of the recess 25

there is provided a positioning lug 27, for the purpose of insuring the proper positioning of the unit in the casing and to prevent it from relative turning therein. The reflector portion is provided centrally with the filament support 28 to which the conductor wires 29 are connected in the usual manner.

According to the invention the inside diameter of the rim portion 11 is somewhat larger than the diameter of the flange 24 of the lamp unit, so that in installing the lamp unit it may be readily inserted into engagement within the rim portion 11, either in the concentric relation of the flexibly movable rim part, as shown in Fig. 3, or with the flexibly movable rim part forced outwardly to a slight degree. It is pointed out in this connection that the internal diameter of the retaining flange 13 of the rim portion, in its concentric relation, as shown in Fig. 3, may be equal to or slightly less than the diameter of the flange 24 of the lighting unit. Upon engagement of the lighting unit within the casing, in seating engagement with the abutment flange 12, the fastening screw 18 is tightened, causing the lower flexibly movable split portion of the rim along the cut 15 to be drawn inwardly out of its normal concentric relation and into tight engagement with the lower side of the flange 24, at the same time pressing the upper side of the flange firmly into engagement with the upper side of the rim 11. The lower portion of the rim at each side of the split 14 is raised slightly above the peripheral outline of the casing rearwardly of the cut 15, as shown clearly in Fig. 2, the flange of the lamp unit being at the same time slid upwardly upon the abutment flange 12. In this manner the lamp unit is firmly secured within the casing, the tightening of the fastening screw 18 causing the rim to be drawn in to the point where it securely clamps about the flange of the unit. It will be understood that the diameter of the rim and its retaining flange relative to the diameter of the lamp unit may be varied to bring about any desired variation in the degree of expansion and contraction of the flexibly movable rim portion to permit the insertion and retaining of the lamp unit.

In Fig. 5, there is shown a modified form of the invention in which a rim portion 11^a is separately formed from the casing 10^a, the rim portion being provided rearwardly of the abutment flange 12^a with an inwardly offset lip 30 fitted within the forward end of the casing 10 and inseparably secured thereto by rivets 31, or by other suitable means such as spot welding. A pair of retaining lugs 20^a is lanced from the lip 30 and bent inwardly therefrom to provide positioning and retaining means for the lug 27 of the lamp unit. This form of the invention permits the casing to be formed from a different material than the rim, for instance the casing may be of plastic or of painted metal, while the rim is of chrome-plated metal. Its cooperation with the lamp unit is the same as in the first embodiment.

In Fig. 6 there is shown the manner in which the separable type of reflector 32 and lens 33 may be adapted for cooperation with the casing of the invention. The reflector is provided with an outwardly projecting rim flange 34 fitted against the rim flange 35 of the lens, the two rim flanges being engaged within the rim portion 11 of the casing in the same manner as the engagement of the flange 24 of the "Sealed Beam" type of lamp unit, the flange 34 of the reflector seating against the abutment flange 12 and the

flange 35 of the lens being engaged and retained by the retaining flange 13.

I have illustrated and described preferred and satisfactory embodiments of the invention, but it will be obvious that changes may be made therein, within the spirit and scope thereof as defined in the appended claims.

Having thus described by invention, what is claimed and desired to be secured by Letters Patent is:

1. In a lamp, a casing comprising a body part and a circumferential rim part permanently connected together, inwardly projecting abutment means permanently connected to said casing at a point within said casing between said body part and said rim part, a retaining flange at the forward edge of said rim part, said rim part including a flexibly movable portion extending partially about its circumference defined by a circumferential cut between said abutment means and said retaining flange, there being a transverse split extending forwardly from said circumferential cut through said retaining flange, and fastening means connected between the opposed edges of said transverse split adapted to contract said flexible rim portion with respect to its normal open relation relatively to said rim part and whereby a lens inserted within said rim portion in opposed relation to said abutment flange means is retained therein through contraction of said flexibly movable rim portion.

2. In a lamp, a casing comprising a body part and a circumferential rim part permanently connected together, a circumferential inwardly projecting abutment flange permanently connected to said casing at a point within said casing between said body part and said rim part, a retaining flange at the forward edge of said rim part, said rim part including a flexibly movable portion extending partially about its circumference defined by a circumferential cut between said abutment flange and said retaining flange, there being a transverse split extending forwardly from a point intermediate the ends of said circumferential cut through said retaining flange, and fastening means connected between the opposed edges of said transverse split adapted to contract said flexible rim portion with respect to its normal open relation relatively to said rim part and whereby a lens inserted within said rim portion in opposed relation to said abutment flange is retained therein through contraction of said flexibly movable rim portion.

3. In a lamp, a casing comprising a body part and a circumferential rim part, a circumferential inwardly projecting abutment flange integrally connecting said body part and said rim part, a retaining flange at the forward edge of said rim part, said rim part including a flexibly movable portion extending partially about its circumference defined by a circumferential cut between said abutment flange and said retaining flange, there being a transverse split extending forwardly from said circumferential cut through said retaining flange, and means adapted to contract said flexible rim portion with respect to its normal open relation relatively to said rim part and whereby a lens inserted within said rim portion in opposed relation to said abutment flange is retained therein through contraction of said flexibly movable rim portion.

4. In a lamp, a casing comprising a body part, having a forward open end, a circumferential rim part inserted in said open end and secured thereto and including an inwardly disposed circumfer-

tial inwardly projecting abutment flange and a retaining flange at its forward edge, said rim part including a flexibly movable portion extending partially about its circumference defined by a circumferential cut between said abutment flange and said retaining flange, there being a transverse split extending forwardly from said circumferential cut through said retaining flange, and means adapted to contract said flexible rim portion with respect to its normal open relation relatively to said rim part and whereby a lens inserted within said rim portion in opposed relation to said abutment flange is retained therein through contraction of said flexibly movable rim portion.

5. In a lamp, the combination with a lamp unit including a lens and a reflector having a peripheral flange, of a casing comprising a body part and a circumferential rim part permanently connected together, inwardly projecting abutment means permanently connected to said casing at a point within said casing between said body part and said rim part, a retaining flange at the forward edge of said rim part, said rim part including a flexibly movable portion extending partially about its circumference defined by a circumferential cut between said abutment means and said retaining flange, there being a transverse split extending forwardly from said circumferential cut through said retaining flange, and means adapted to contract said flexible rim portion with respect to its normal open relation

relatively to said rim part and whereby the flange of said lamp unit inserted within said rim portion in opposed relation to said abutment flange is retained therein through contraction of said flexibly movable rim portion.

6. In a lamp, the combination with a lamp unit including a lens and a reflector having a peripheral flange, a casing comprising a body part and a circumferential rim part permanently connected together, a circumferential inwardly projecting abutment flange permanently connected to said casing at a point within said casing between said body part and said rim part, a retaining flange at the forward edge of said rim part, said rim part including a flexibly movable portion extending partially about its circumference defined by a circumferential cut between said abutment flange and said retaining flange, there being a transverse split extending forwardly from a point intermediate the ends of said circumferential cut through said retaining flange, and fastening means connected between the opposed edges of said transverse split adapted to contract said flexible rim portion with respect to its normal open relation relatively to said rim part and whereby the flange of said lamp unit inserted within said rim portion in opposed relation to said abutment flange is retained therein through contraction of said flexibly movable rim portion.
